INTERNAL SPINAL FIXATION MEANS

Charles B. Thomas, 701 Pendleton St., Greenville, S.C.
Filed June 25, 1963, Ser. No. 290,482

2 Claims. (Cl. 128—92)

The present invention relates to an internal spinal fixation, and more particularly to a rigid fixation extending upwardly from the pelvic bone to the spinal column and securable to both to support the spinal column on the pelvic bone.

It is the primary purpose of the present invention to relieve pressure from the lumbar portion of the spinal column, thereby to distract, flex and immobilize the lumbar spine. This is accomplished in the preferred embodiment of the present invention by a pair of support members mounted on opposite sides of the spinal column with base portions secured to the iliac crest of the pelvic bone, rigid body portions converging upwardly from the base portions to the spinal column, and spinal column engaging portions at the upper ends of the body portions and secured to the spinal column. With this construction the load or pressure on the spinal column is transmitted through the support members to the pelvic bone, thereby relieving pressure from the lumbar portion of the spinal column below the spinal column engaging portions.

The body portion may be of an extensible construction, such as a turnbuckle, to permit an increase or other adjustment of the spacing between the base portions and spinal column engaging portions after these portions have been secured to their respective body elements.

To permit ease of installation, the preferred embodiment of the present invention includes double pivot swivel joints at both ends of the body portions for pivotal connection of both the base portions and the spinal column engaging portions. With these swivel joint connections relative angular movement of the spinal column engaging portions with respect to the base portions is possible during installation of the present invention.

In the preferred embodiment the base portions and the spinal column engaging portions are secured to their respective body elements by means of spike-like elements that extend from these portions into the body elements. The spikes from the base portions extend laterally through the iliac crests of the pelvic bone to fix the position of the base portions and are prevented from withdrawing from the iliac crests by screws or other elements extending downwardly into the iliac crests from locations in the base portions above the spikes. The spikes of the spinal column engaging portions extend laterally through the spinal column and abut the opposing spinal column engaging portions to fix these portions in place. Separation of the spinal column engaging portions is prevented by means, such as bolts, secured to both portions and holding them against relative movement in spike abutting relation.

Other and further features and advantages of the present invention will be apparent from the following description and accompanying drawings in which:

FIG. 1 is a diagrammatic view of the lower thoracic cage, lumbar spine and pelvic bone of a human body with the preferred embodiment of the internal spinal fixation of the present invention secured to the spinal column and the pelvic bone;

FIG. 2 is an enlarged rear elevational view of one of the pair of support members of the internal spinal fixation illustrated in FIG. 1;

FIG. 3 is an enlarged horizontal sectional view of the internal spinal fixation of FIG. 1 taken along the line 3—3 of FIG. 1;

FIG. 4 is a side elevational view of the upper portion of the support member of FIG. 2; and

2

FIG. 5 is a side elevational view of the lower portion of the support member of FIG. 2.

The internal spinal fixation 10 of the preferred embodiment of the present invention illustrated in the figures 5 comprises a pair of support members 12 secured to the pelvic bone 14 on opposite sides of the spinal column 16 and extending upwardly to a securement to the spinal column 16.

Each of the support members 12 has a base portion 18 mounted on the iliac crest 19 at the top of the pelvic bone 14. The base portion 18 is connected to a body portion 20 that extends upwardly to a spinal column engaging portion 22 secured to the spinous processes 23 of the spinal column 16.

15 In the embodiment illustrated the body portions 20 are in the form of turnbuckles to provide for extension or elongation of the body portions for relief of pressure in the lumbar portion of the spinal column below the attachment of the spinal column engaging portions 22.

20 Each of the body portions 20 is formed with a lower half 24 having a tapped bore opening upwardly and in which is received a threaded turnbuckle rod 28, which when rotated advances and retracts in the bore 26 of the lower half 24. The position of the rod 28 in the lower half 24 can be fixed by tightening a lower lock nut 30 at the top of the lower half 24. The turnbuckle rod 28 extends upwardly into the tapped bore 34 of the upper half 32 of the body portion 20 and is similarly rotatable therein to advance and retract and can be fixed with 30 respect thereto by tightening the upper lock nut 36.

The body portions 20 are connected to the base portions 18 and spinal column engaging portions 22 by double pivot swivel joints 38 and 48. Each lower swivel joint 38 connects the lower end of the lower half 24 of the body portion 20 to the base portion 18. The lower swivel joint 38 has a flanged lug 40 extending downwardly therefrom and seated for free rotation in a shouldered hole 42 in the base portion 18. The swivel joint 38 is bifurcated and receives a pivot flange 44 extending from the lower half 24 of the body portion 20, which flange 44 is pivotally mounted in the bifurcated swivel joint by means of a pivot pin 46. With this construction the body portion 20 can be positioned at substantially any angle with respect to the base portion 18.

45 Each upper swivel joint 48 is substantially identical to the lower swivel joints 38 and connects the upper half 32 of a body portion 20 to the spinal column engaging portions 22. The upper swivel joints 48 have flanged lugs 50 that are seated for free rotation in shouldered holes 52 in the spinal column engaging portions 22. The upper swivel joints 48 are also bifurcated to receive the pivot flange 54 extending from the upper end of the upper half 32 of the body portion 20 with the flange 54 pivotally secured to the joint 48 by a pivot pin 56. As a result the spinal column engaging portions 22 may be positioned at substantially any angle with respect to the body portions 20.

For attachment of the base portions 18 to the iliac crest 19, each base portion is formed with a top component 58 that can be positioned on top of an iliac crest 19 and a downwardly extending component 60 that can be positioned against the face of the iliac crest 19. The base portions 18 are secured to the iliac crests 19 by a plurality of spikes 62 extending laterally from the downwardly extending components 60 into the iliac crests 19. The base portions 18 are locked in place by screws 64 that are screwed downwardly into the iliac crests 19 through holes 66 provided in the top component 58 of the base portions 18.

70 The spinal column engaging portions 22 of the preferred embodiment are in the form of vertically extending plates

68 secured on opposing sides of the spinal column 16 by a plurality of staggered spikes 70 extending laterally from the plates 68 through the spinous processes 23 with the outer tip 72 of the spikes 70 abutting the opposing plates 68. The plates 68 are locked in this spike abutting position by bolts 74 extending through slots 76 in the plates 68, with the bolts secured by nuts 78 so that the plates 68 are held together between the heads 80 of the bolts and the nuts 78. The slots 76 in the plates 68 extend vertically to permit vertical positioning of the bolts 74 in the spinous processes 23.

To attach the internal spinal fixation 10 to the body elements of a patient, the vertical plates 68 of the spinal column engaging portions 22 are first placed on opposite sides of the upper lumbar spinous processes 23. The bolts 74 are then passed through the slots 76 of one plate, through the spinous processes 23, and through the corresponding slots on the opposite plate. The nuts 78 are then placed on the bolts 74 and tightened until the spikes 70 pass through the spinous processes 23 and their tips 72 abut the opposing plates 68.

The base portions 18 are then placed on the iliac crests 19 and the spikes 62 driven into the pelvic bone 14 until the downwardly extending components 60 of the base portions 18 are against the iliac crests 19. The screws 64 are then screwed downwardly through the top component 58 into the iliac crest.

The turnbuckle body portions 18 are then adjusted by rotating the turnbuckle rods 28 with respect to the lower body halves 24 and upper body halves 32 to elongate the body portions 28, increasing the spacing between the base portions 18 and spinal column engaging portions 22, and thereby relieving the pressure on the lower lumbar spinal column to provide distraction, immobilization and flexion thereof.

The present invention has been described in detail above for purposes of illustration only and is not intended to be limited by this description or otherwise except as defined in the appended claims.

I claim:

1. An internal spinal fixation for relieving pressure in the lower lumbar portions of a spinal column in a human body comprising a pair of converging, rigid, support means adapted to be attached to and extend between the iliac crests of the pelvic bone and the spinous processes of the spinal column on each side of the spinal column to support the spinal column on the pelvic bone; each of

5 said pair of support means comprising an elongate rigid body means having means therein for adjusting the length thereof and including double pivot swivel joints on each end thereof, a base means pivotally secured to one of said double pivot swivel joints on one end of said body means and adapted to be attached to an iliac crest of the pelvic bone on opposite sides of the spinal column, and a spinal column engaging means pivotally secured to the other of said double pivot swivel joint on the other end of said body means and adapted to be attached to the spinous processes on opposite sides of the spinal column.

10 2. An internal spinal fixation for relieving pressure in the lower lumbar portions of a spinal column in a human body comprising a pair of converging, rigid, support means adapted to be attached to and extend between the iliac crests of the pelvic bone and the spinous processes of the spinal column on each side of the spinal column to support the spinal column on the pelvic bone; each of said pair of support means comprising an elongate rigid body means including double pivot swivel joints on each end thereof, a base means pivotally secured to one of said double pivot swivel joints on one end of said body means and including spike-like elements secured thereto to adapt said base means for attachment to an iliac crest of the pelvic bone on opposite sides of the spinal column, and a spinal column engaging means secured to the other of said double pivot swivel joints on the other end of said body means and including spike-like elements secured thereto to adapt said spinal column engaging means for attachment to the spinous processes on opposite sides of the spinal column, said body means comprising adjustable, extensible turnbuckles so that said body means may be adjustably elongated to adjust the spacing between said base means and said spinal column engaging means.
